UNITED STATES PATENT OFFICE.

ALEXANDER KUCZOR, OF CUDAHY, WISCONSIN, ASSIGNEE OF ONE-THIRD TO ANDREW KUCZOR, OF CUDAHY, WISCONSIN.

SCREEN FOR WINDOWS.

1,125,128.

Specification of Letters Patent. Patented Jan. 19, 1915.

Application filed May 21, 1914. Serial No. 389,848.

To all whom it may concern:

Be it known that I, ALEXANDER KUCZOR, a citizen of the United States, and resident of Cudahy, in the county of Milwaukee and State of Wisconsin, have invented new and useful improvements in Screens for Windows, of which the following is a description, reference being had to the accompanying drawings, which are a part of this specification.

This invention has for its object to provide screens for windows which will be automatically extended to cover the openings left by the sashes whether they are partly or entirely opened, the screens being connected with the upper edge of the upper sash and the lower edge of the lower sash and being mounted on rollers which permit them to be drawn out as the sashes are opened and which will rewind them as the sashes are closed.

Another object of the invention is to perfect details of construction in screens for windows.

With the above and other objects in view the invention consists in the screen for windows as herein claimed and all equivalents.

Referring to the accompanying drawings in which like characters of reference indicate the same parts in the different views: Figure 1 is a front view of a window provided with screens constructed in accordance with this invention; Fig. 2 is a side view thereof with the side plate removed showing the arrangement of cords and springs for controlling the position of the sash and for rewinding the screen on the rollers; Fig. 3 is a longitudinal sectional view on the plane of line 3—3 of Fig. 1; Fig. 4 is a transverse sectional view on the plane of line 4—4 of Fig. 1; Fig. 5 is a similar view on the plane of line 5—5 of Fig. 1; Fig. 6 is a detail view showing the removable sill and apron for permitting access to the lower screen roll; Fig. 7 is a similar view of a modified form thereof; Fig. 8 is a sectional front view of one side of a window provided with a screen on the upper sash only; Fig. 9 is a side view thereof; Fig. 10 is a front view of one side of a window provided with a screen on the lower sash only; and, Fig. 11 is a side view thereof.

In these drawings 10 indicates a window casing having a lower sash 11 and an upper sash 12 slidably mounted therein as usual. Instead of these sashes being hung

with counterweights, the suspension cord 13 after passing over the upper pulley 14, as usual, connects with a coil spring 15, the other end of which is connected by a cord 16 passing around a pulley 17 with the lower end of the same sash. The tension given to the cord 16 by the coil spring 15 is sufficient to give the pulleys and their parts a friction that will hold the sashes in any position in which they are placed.

The sides of the window casing are extended above and below the window opening and are notched or recessed to provide half bearings 18 and 19 respectively within which are fitted reduced portions of rollers 20 and 21 respectively on which are wound screen members 22 and 23, the former being attached to the upper edge of the upper sash 12, while the latter is attached to the lower edge of the lower sash 11.

At the ends of the rollers 20 and 21 are reels or spools 24 around which are wound cords 25 and 26 respectively, the cords being wound in the opposite direction to the winding of the springs and being connected to a coil spring 27, the coil spring from the cord 25 of the upper sash screen roll being connected with the cord 16 of the upper sash, and the spring 27 connecting with the cord 26 of the lower sash screen roll also connecting with the cord 13 of the lower sash. Thus each screen roller has a tensioned cord connection with the sash to which that screen is connected and the movements of either sash impart corresponding movements to the screen roller of the screen connected with that sash, the direction of movement of the screen rollers thus produced being such that the screen is reeled off of the roller as the sash is opened and the screen is wound on the roller as the sash is closed.

The connection of the screen to the sash is made by a metal binding strip 28 at the end of the screen being secured to the sash by screws 29 so as to be readily attached and detached, and the ends of the metal strip 28 of the lower sash screen 23, as well as the side edges of said lower sash screen, are guided in a groove formed by cutting out the rear edge of the lower part of the window guide strip 30 and fitting an angle iron 31 therein with its flange spaced from the cutaway portion of the guide strip and continuing the guide surface for the lower

sash. The edges of the screen 22 of the upper sash bear against the parting strip 32 between the upper and lower sash to complete the closure, while a sealing strip 33 on the bottom of the upper sash extending to near the glass of the lower sash avoids the formation of an open space between the two sashes. The cords 23 from the upper sash screen roller may be guided over suitable pulleys 34 so as to avoid conflict between the cords of the upper and the lower sashes.

The screen roller 20 is accessible by removing the front plate 35 of the casing and it may be readily removed from its half bearing if desired, and the same is true of the lower screen roller 21, for the lower part 36 of the bearing thereof is carried by the apron 37 with the attached sill 38, it being only necessary to remove this apron to give access to the lower roller 21 and permit of its removal if desired.

In Fig. 7 is shown a modified form of the bearing for the lower roller 21 in which the notch 19 is bent to a hook shape to afford the half bearing for the roller, and the apron and sill alone are permanently connected together.

By means of this invention the opening of either sash requires nothing further to be done in order to properly screen the opening, the sash itself drawing the screen off of its roller as the sash is being opened, and the movement of the sash imparting movement to the roller to rewind the screen thereon as the sash is being closed. This gives the same screening effect as screens known as "all-over screens," without the objectionable presence of the screen alongside of the glass where it obstructs the vision and serves to catch dust to be beaten against the glass during rain storms.

The invention does not necessitate the presence of screens for both sashes, as either sash may be alone provided with the screen and serve the purpose as long as the other sash remains closed, such construction being shown in Figs. 8 and 9, where the upper sash alone is provided with the screen, and in Figs. 10 and 11, where the lower sash alone is provided with the screen.

What I claim as new and desire to secure by Letters Patent is:

1. A screen for windows, comprising a suitably mounted roller, a screen wound thereon and connected with one end of a window sash, a cord wound upon the roller in the opposite direction to the winding of the screen, a coil spring connected with the said cord, a second cord connected with the coil spring and connected with the other end of the window sash.

2. In combination with a window casing

having a sash slidably mounted therein and a pulley at each end of the travel of the sash, a cord connected with the sash and passing over the upper pulley, a cord connected with the sash and passing around the lower pulley, a coil spring connecting said cords, a roller suitably mounted in the window casing, a screen wound upon the roller and connected with one end of the sash, cord wound upon the roller in the opposite direction to the winding of the screen, and a spring connecting said cord to the other end of the sash.

3. The combination with a window casing having upper and lower sash members slidably mounted therein and having pulleys at the ends of the travel of each sash, cords connected with each sash and passing around the upper and lower pulleys respectively, coil springs connecting the cords of each sash, a roller journaled in the upper part of the window casing, a roller journaled in the lower part of the window casing, a screen wound upon the upper roller and connected with the upper sash, a screen wound upon the lower roller and connected with the lower sash, cords wound upon the rollers in the opposite direction to the winding of the screens, and a coil spring connected with each of such cords and also connected with the cords passing around the pulleys, the spring of the cord of the lower roller connecting with the cord of the lower sash passing over the upper pulley, and the spring of the cord of the upper roller connected with the cord of the upper sash passing around the lower pulley.

4. The combination with a window casing having upper and lower sashes slidably mounted therein and provided with pulleys at the ends of the travel of the sashes and with roller compartments at the top and the bottom thereof containing half bearings, rollers journaled in the half bearings in the roller compartments, screens wound upon the rollers and connected with the sashes, cords connected with the sashes and passing around the upper and lower pulleys, coil springs connecting the cords of each sash, cords wound around the rollers in the opposite direction to the winding of the screens, coil springs connected to said cords and also connected to the cords passing around the pulleys, and removable front plates for the roller compartments permitting access to the rollers.

In testimony whereof, I affix my signature, in presence of two witnesses.

ALEXANDER KUCZOR.
